UNITED STATES PATENT OFFICE.

JAMES D. RANDALL, OF CINCINNATI, OHIO, ASSIGNOR TO THE J. D. RANDALL COMPANY,
OF CINCINNATI, OHIO, A CORPORATION OF OHIO.

CHANNERER FOR AWLS.

1,125,394.

Specification of Letters Patent.

Patented Jan. 19, 1915.

Application filed September 9, 1911. Serial No. 648,558.

To all whom it may concern:

Be it known that I, JAMES D. RANDALL, a citizen of the United States of America, and resident of Cincinnati, county of 5 Hamilton, and State of Ohio, have invented certain new and useful Improvements in Channelers for Awls, of which the following is a specification.

My invention relates to a channerer for 10 use in sewing machines adapted to stitch heavy material such as leather, rubber, etc.

The function of the channerer is to form 15 a groove or cut between the holes which are formed by the awl, the groove being to receive the thread between the holes so as to submerge or bury the stitching.

The object of my invention is a channerer 20 of simple construction which will remain firmly in line with the stitching and may be attached readily in place for use.

In the accompanying drawings, I have 25 illustrated a channerer embodying my invention and have illustrated it in connection with the parts of the sewing machine necessary to illustrate its connection therewith.

Figure 1 is an elevation of parts of a 30 sewing machine and of the channerer embodying my invention. Fig. 2 is a view in elevation of my channerer, in combination with an awl. Fig. 3 is a view taken at right angles to Fig. 2. Fig. 4 is a perspective view of the channerer embodying my invention.

Referring to the parts: My channerer is 35 used in combination with the usual awl B. The awl B punches the usual holes in the material D for the passage of the needle E, the foot e holding the material intermittently in place while the needle is forming

the loop. The material is fed beneath the awl so that it makes a series of holes in the material.

The channerer embodying my invention comprises a spur having at its lower end a wedge-shaped cutting edge a' , and having near its upper end a collar a^2 projecting transversely from the spur, and having a longitudinal bore a^3 and a transverse bore a^4 , to receive a set screw a^5 for fastening the channerer upon the awl. The wedge-shaped cutting edge a' is made at least of a width equal to the distance between the holes which are punched by the awl B. The bore a^3 is of a diameter such as to permit the collar a^2 to be slipped over the awl B.

In use: The collar a^2 being placed over the awl and the set screw a^5 being tightened, the channerer is held firmly in alignment with the row of stitching. The operation 60 of securing the channerer upon the awl is a simple one and it may be adjusted readily upon the awl, to vary the depth of the channel which is made by it.

What I claim is:

The combination of an awl and a channerer consisting of a spur, a collar projecting from one side of the spur and having a sliding connection with the awl, and a set screw extending through the collar and adapted to engage the awl for locking the channerer in any desired position upon the awl.

JAMES D. RANDALL.
